UNITED STATES PATENT OFFICE.

WILLIAM J. STEWART, OF PHILADELPHIA, PENNSYLVANIA.

DESIGN FOR A BADGE, BUTTON, OR ARTICLE OF SIMILAR NATURE.

61,124.

Specification for Design.

Patented June 20, 1922.

Application filed February 26, 1920. Serial No. 361,562. Term of patent 3½ years.

To all whom it may concern:

Be it known that I, WILLIAM J. STEWART, a citizen of the United States, residing in the city and county of Philadelphia, State of Pennsylvania, have invented a new, original, and ornamental Design for a Badge, Button, or Article of Similar Nature, of which the following is a specification, reference being had to the accompanying drawing, forming part thereof.

Figure 1 is a face view of a badge, button, or article of similar nature showing my new design.

I claim:

The ornamental design for a badge, button, or article of similar nature as shown.

WILLIAM J. STEWART.
